S. SAWYER.

Shell.

No. 13,799.

Patented Nov. 13, 1855.

UNITED STATES PATENT OFFICE.

S. SAWYER, OF FITCHBURG, MASSACHUSETTS.

IMPROVED COMPOUND PROJECTILE.

Specification forming part of Letters Patent No. 13,799, dated November 12, 1855.

To all whom it may concern:

Be it known that I, SYLVANUS SAWYER, of Fitchburg, in the county of Worcester and State of Massachusetts, have invented an Improved Bomb-Shell; and I do hereby declare that the same is fully described and represented in the following specification and the accompanying drawings, in which—

Figure 1 denotes a side elevation of the same; Fig. 2, a top view of it; Fig. 3, a bottom view of it. Fig. 4 is a central and longitudinal section of it; Fig. 5, a transverse and horizontal section of it.

The said projectile is intended to be discharged from a cannon or howitzer provided with helical grooves in its bore essentially like those in a rifle, the projectile being made with wings or guides to enter such grooves, and so far therein that during the discharge of the piece the grooves may impart to the shell a whirling or rotary motion on its axis, which shall be maintained during its flight or course toward the object to which it may be directed.

In applying to the external surface of conical or cylindro-conical shells lead, when such shells have been made of cast-iron, it has been customary to cast the lead on the cylindrical surface of the shell, or that part of it which during its passage through the bore of the gun would be likely to rub against the same, the lead or soft metal having been applied as a protection to the gun, or as a means of not only preventing that wear or tear of it which would result were the iron surface of the shell to be allowed to come in contact with the inside surface of the bore, but the bursting of the gun, which is liable to follow from the choking of it by the shell, where such friction or tearing of the bore is produced. Under these circumstances it has been found that, owing to

the rapid passage of flame over the surface of the lead during the movement of the shell through the bore, such lead will be instantaneously ripped or melted off the shell, and consequently rendered useless for the purpose for which it was applied thereto. I have endeavored to make a shell in such manner as to stop the passage of the flame by it, or prevent it from tearing or melting off the anti-friction metal. For this purpose I so construct the shell and apply the anti-friction metal thereto that the force of the explosion,

acting in conjunction with the hard metal at the butt or rear end of the shell, shall expand a portion of such anti-friction metal, so as to press it firmly against the inner surface of the bore of the piece and cut off the passage of the flame by the shell or its leaden or anti-friction coating. Furthermore, in order to fasten the anti-friction metal firmly to the cast-iron shell or body, I first coat the latter with tin, or some metal which will have a stronger affinity for the cast-iron and the lead or anti-friction metal than the latter has for the iron. This done, I cast on and around the metallic coating so applied the coating or case of lead or anti-friction metal. I also form the rear part of the iron case or shell frusto-conical or tapering, and apply to such an extra thickness of anti-friction metal, which, when an explosion of the charge of the gun takes place, shall force or crowd the surplus anti-friction metal up the conical or tapering surface joining the cylindrical body of the shell, the said surface serving to expand the ring of metal on it, and cause it to fit closely to the bore of the gun, and so as to prevent windage, and the passage of flame by such ring to such extent as to tear or melt the anti-friction metal in advance of the ring. Besides the above, I extend the anti-friction metal beyond and around the screw-plug of the shell, and screw into it the explosive cap of the shell, arranging such cap directly over the screw-plug, and so that when the shell is thrown against an obstacle point first its momentum shall compress the anti-friction or soft metal, so as to cause it to give way and let the explosive cap with force down, so as to compress the percussion wafer or priming arranged on top of the screw-plug or in the explosive cap, as the case may be.

In the drawings, A shows the cast-iron hollow body of the shell, which, when the projectile is used, is to be charged or loaded with powder or other proper material, such body, generally speaking, being formed cylindro-conical, and provided with a screw-plug, B, and a series of helical wings, E E E E E, arranged as seen in the several figures.

C exhibits the covering of tin, while D shows the coating of lead or anti-friction metal, it being extended up above and around the screw-plug B, and provided with a female screw, as

seen at *d d* in Figs. 1, 2, and 4, such screw serving to receive a male screw, *e e*, formed on the explosive cap *F*. The said cap *F* constitutes a cover to the screw-plug *B*, which is provided with one or more vent-holes, *f f*, leading down through it. Above the top of the said plug, and between it and the cap *F*, or in the latter, the percussion priming or wafer is to be placed. Under all ordinary circumstances the compressible anti-friction metal sustaining the screw-cap *F* will retain it from being forced down upon the priming, the cap being formed with a shoulder, *h h*, to rest on the metal. When the shell is forced from the gun, the cap first comes in contact with the object fired at, and by such and the force or momentum of its flight will be driven down, so as to compress the percussion-priming and to cause an explosion of it, the holding metal yielding under the force of the impingement of the shell and suffering the explosive cap to so act. The wings *E*, as well as the body of the shell, are to be coated with the tin and anti-friction metal, which should also extend over the butt or rear end of the shell and its tapering part *a a*, as seen at *b b* in Fig. 3.

Previous to inserting the shell in the piece of ordnance a patch or cloth hood or bag may be drawn over it, partially or wholly, so as to separate its sides from the inside surface of the bore. A shell constructed on the above plan has been found exceedingly effective in preventing friction and wear of the gun and the consequent choking and bursting of it which might ensue, besides being of great advantage so far as saving of ammunition is concerned.

At *b b*, Fig. 4, I have exhibited the annulus

of lead or soft metal extending around the tapering or conical part *a a* of the cast-iron body of the shell. When the explosion of the charge of the gun takes place, this annulus will be driven up the tapering part *a a* and expanded thereby, and so as to produce effects as stated.

I claim—

1. Combining with the butt or flat rear end of the cylindro-conical iron shell a layer of lead or softer metal than that of which the body of the shell is composed, and united or not to a layer of such metal extended around the sides of the shell, as described, the same operating in manner as specified while the shell is being projected through the bore of a gun by a discharge of the powder therein.

2. Making the rear part of the shell tapering or conical, as seen at *a a*, combining therewith a ring or annulus, *b b*, of lead or its equivalent, the same being substantially in manner and for the purpose as hereinbefore specified.

3. Confining the explosive screw-cap to the body of the shell by means of a softer or yielding metal or casing, which, when the cap or shell shall strike an object, shall give way under the force of the blow and let the cap down with force, so as to compress the percussion wafer or priming in it or on the main screw, stopper, or plug, and so as to create an explosion thereof, as stated.

In testimony whereof I have hereunto set my signature this 9th day of October, A. D. 1855.

SYLVANUS SAWYER.
